UNITED STATES PATENT OFFICE.

JOHN H. GILES AND DONALD M. GILES, OF PHILADELPHIA, PENNSYLVANIA.

DYEING MACHINE.

Application filed April 19, 1922. Serial No. 555,563.

To all whom it may concern:

Be it known that we, JOHN H. GILES and DONALD M. GILES, both residing at Philadelphia, county of Philadelphia, and State 5 of Pennsylvania, have invented certain new and useful Improvements in a Dyeing Machine, of which the following is a specification.

This invention relates to improvements in 10 yarn dyeing machines and more particularly to improvements in which skeins of yarn are dyed while held by yarn sticks mounted in inner and outer supporting members.

15 In such machines, there is usually provided a vat for the dye liquor through which extends a shaft. Mounted on the shaft is a pair of yarn sticks supporting members between which the sticks extend.

20 A similar pair of supporting members is also provided between which a second series of yarn sticks is mounted, the members of the second series lying parallel to and somewhat nearer the shaft than the outer

25 series. The yarn in the skein form is held between corresponding sticks of the inner and outer series, the supporting members being relatively adjustable so as to put a slight tension on the yarn. With the yarn 30 relatively taut, the shaft with the stick supporting members is then lowered and upon being revolved, the sticks with the yarn thereon are successively immersed in the dye liquor.

35 One of the objects of this invention is to provide a new and improved means for adjusting the relative positions of the yarn stick supporting members of such a dyeing machine to place tension on the yarn. The

40 adjusting means forming the subject-matter of this application for patent are believed to be a material improvement upon the devices for the purpose included in our patent of the United States numbered 1,146,324, dated July 13, 1915, by reason of the advantages hereinafter explained.

Another object is to provide a new and improved means for adjusting the tension on the yarn in a dyeing machine, the ad-

justing means being easily operable without 50 the danger of the operative touching the yarn in position on the sticks.

Still another object is to provide a new and improved means for adjusting the tension on the yarn in a dyeing machine, the 55 adjusting means being operable to produce a fine adjustment with no danger of entangling the yarn.

Other objects and aims of the invention, more or less specific than those referred to 60 above, will be in part obvious and in part pointed out in the course of the following description of the elements, combinations, arrangements of parts and applications of 65 principles, constituting the invention; and the scope of protection contemplated will be indicated in the appended claims.

In the drawings in which we show a preferred form of embodiment of our invention:

70 Figure 1 is a transverse sectional view of a yarn machine of the type described.

Figure 2 is a longitudinal sectional view of a similar machine.

Figure 3 is a detail view of the parts 75 forming our improved tensioning means.

With reference now to the drawings in which similar reference characters refer to similar parts throughout the several views thereof, the reference character 1 designates 80 a vat for dye liquor, having straight vertical sides 2 and a rounded bottom 3. Mounted in arcuate slots 4, 4 in the side walls is a shaft 5 suitably counterweighted by means of cables 6, 6 which pass over pulleys 7, 7 on a shaft 8, to be attached to weights 9, 9. By this arrangement the shafts with the parts mounted thereon may be readily moved up and down in the slots.

85 Mounted on shaft 5 is a pair of outer yarn sticks supporting members or heads 10, 10, in opposed faces in which are suitable brackets to support the yarn sticks 11. Mounted in suitable brackets 12, 12 on the spokes 13, 13 of the outer stick supporting members is a pair of inner stick supporting members or heads one of which is shown at 14. The inner pair of heads is

also provided with means to support a series of yarn sticks 15, 15. The yarn in the skein form is looped about corresponding sticks of the inner and outer series and in order to 5 tauten the skeins, the stick supporting members are moved a short distance relatively to one another, thus increasing the distance between the corresponding sticks.

The shaft 5 with its attached members is 10 now lowered in the arcuate slot and upon rotation successive skeins are immersed in the dye liquor contained in the bottom of the vat, this liquor being suitably heated by steam introduced through a pipe 16. 15 The usual trip and star wheel devices are provided so that the sticks will be given a stepwise rotation in their bearings upon the rotation of shaft 5 so as to insure the complete immersion and dyeing of all parts 20 of the skeins.

The description so far relates to yarn dyeing machines of well known construction and is given here merely to make clear the operation of our improvement which, as 25 stated, provides means for producing a relative adjustment of the stick supporting members, so as to tauten the yarn held thereon.

To provide such adjustment there is 30 mounted on a suitable bracket 17, on one of the spokes of the outer yarn stick head, a shaft 18 provided with a squared head 19 at its outer end. At its inner end the shaft carries a worm 20 meshing with a worm gear 21, mounted on a shaft 21^a, extending between the heads and supported in brackets 22 on the spokes. Rigidly mounted on the worm gear 21 is a crank arm 23 extending radially outwardly. If desired the crank 23 35 may be cast as an integral part of the gear 21. In its extremity the crank arm 23 has a slot 24 in which rides a pin 25 mounted on, or formed as an integral part of one of the inner yarn stick supporting members.

40 The construction above described is to be understood as mounted on a spoke of one of the outer yarn supporting heads but to insure that the heads of the inner series will be moved simultaneously so as to maintain the bearings for individual sticks in 45 registry at all times, the shaft 21^a extends across the machine as indicated, Fig. 2, and is provided at its other end with a crank arm engaging a pin on the other inner yarn stick supporting member, the shaft being 50 suitably supported on the other outer supporting member in a bracket corresponding to 22. By such an arrangement, the partial rotation of the shaft 21^a by means of shaft 55 18, worm 20, and worm gear 21 will be transmitted by the crank arms to the two inner yarn stick supporting members simultaneously, and this movement relative to the outer supporting members serves to 60 tauten the skeins. The shaft 18 may be 65

turned by means of a wrench or other suitable tool applied to the squared head and shaft 18 is turned in one direction to tauten the skeins and in the other, to loosen them so that the yarn may be freely removed from 70 the machine when the dyeing is completed. On working the adjusting means set out in our patent aforesaid, the worm shaft and gearing multiply the force to tension the skeins, and after considerable experience 75 with those devices it has been found that the proper tension can only with difficulty be closely determined, particularly in the somewhat hurried and more or less casual treatment of the machines in every day running. With the crank arm 23 and its operating contrivances, the machine attendant, even though he be not an old and trained dyer, soon learns by the sense of 80 feeling to impress quickly upon the skeins 85 the tension ascertained by practical experience to be demanded by any given kind or quality of yarn and the special dyeing process in hand. The extended crank arm on the pinion does not multiply the force applied, 90 and the reaction felt by the operative is a much more practical and accurate guide to 95 the proper tension.

It will be understood that the new and improved means by which the two yarn stick 100 supporting members are moved relatively to one another, may be mounted in various ways and the construction is not limited to the exact arrangement shown. The construction shown in the drawings is a convenient 105 and perhaps preferable way in arranging the parts to perform the desired functions and it will be seen that a convenient means is provided for tautening the skeins with close 110 adjustment of tension. Preferably the device is to be mounted on the outer faces of the yarn stick supporting members as shown in Figure 2, in which position it can be 115 readily operated without any danger of the operative coming in contact with the yarn. Furthermore, by extending the shaft 18 radially so that its squared end lies adjacent the periphery of the outer stick supporting member, the skeins may be tautened while the shaft 5 is in its lowered position. The 120 device is constructed of simple elements which are not likely to get out of order and which will not readily wear to the point of ineffectiveness.

While the particular dyeing machine herein shown is constructed so as to have its inner member supported in the outer member, it will be understood that the usefulness of the adjustment means is not limited to such a construction, being adaptable for use in any similar machine in which there are yarn sticks supporting members which must be moved relatively to one another to 125 tension the yarn. It will be further understood that the adjusting means is not limited 130

to a machine in which there are but two inner and two outer yarn stick supporting members. It is possible, of course, to construct a machine in which there will be used heads 5 intermediate the end heads, the intermediate yarn stick supporting head providing bearings on either face for yarn sticks. The adjusting means will be equally useful with such a machine as it is only necessary to 10 continue the shaft 21^a and provide additional cranks thereon to engage pins on all of the heads.

As many changes could be made in this 15 construction without departing from the scope of the following claims, it is intended that all matter contained in the above description or shown in the accompanying drawing shall be interpreted as illustrative only and not in a limiting sense.

20 Having thus described our invention what we claim as new and desire to secure by Letters Patent is:

1. The combination with a dyeing machine comprising a liquor vat and inner 25 and outer yarn-stick supporting members, of means to move said inner members relative to said outer members, said means comprising a shaft provided with a worm mounted on one of said outer members, a 30 worm gear revolvably supported in said outer member adapted to be revolved by said worm and cranks movable by the rotation of said gear, the ends of said cranks engaging said inner yarn stick supporting members.

35 2. The combination with a dyeing machine comprising a liquor vat and outer and inner yarn stick supporting members revolvable therein, of means to give said inner members a partial rotation relative to said 40 outer members, said means comprising cranks pivotally mounted on said outer members and engaging said inner members and means to move said cranks on their pivots.

45 3. The combination with a dyeing machine comprising a liquor vat and inner and outer yarn stick supporting members revolvable therein, of means to change the relative positions of said members including 50 cranks pivotally mounted on one pair of said members and engaging pins on the other members, and means to move said cranks on their pivot.

55 4. The combination with a dyeing machine comprising a liquor vat and inner and outer yarn stick supporting members revolvably mounted therein, of means to change the relative positions of said members, said means including a worm gear 60 mounted on one of said members, cranks movable with said worm gear, and engaging pins on the other members, and means to give a partial rotation to said gear whereby to cause the ends of said cranks to 65 describe an arc.

5. The combination with a dyeing machine comprising a liquor vat and inner and outer yarn stick supporting members revolvably mounted therein, of means to change the relative positions of said members, said means including a shaft mounted on one pair of said members and provided with a worm, a worm gear mounted on one of said members and meshing with said worm on said shaft, cranks movable with 70 said gear and having slotted extremities, pins on said other yarn stick supporting members, engaged in said slots and means on said shaft whereby it may be rotated.

6. In a yarn dyeing machine, in combination, a vat, a shaft mounted therein, a pair of outer yarn stick supporting members mounted on said shaft, a pair of inner yarn stick supporting members movably mounted in said outer members, a rotatable shaft radially mounted in one of said outer members and provided with a worm, a gear meshing with said worm pivotally mounted on said outer member, cranks rigidly attached to said pivot and having slotted extremities, 80 pins on said inner members engaged in said slots, and a squared head on the shaft whereby it may be rotated to cause the cranks to move the inner supporting members.

7. The combination with a dyeing machine, comprising a liquor vat and pairs of inner and outer yarn stick supporting members adapted to be revolved into said vat, of means to move the members of one of said 100 pairs of supporting members relatively to the members of the other pair while preserving the registry of the moved members, said means comprising cranks pivotally mounted on the members of one of said 105 pairs, engaging pins on the members of the other of said pairs, and means to cause said cranks to move on their pivots.

8. In a yarn dyeing machine, in combination, a liquor vat, a shaft revolvable adjacent thereto, a pair of outer yarn stick supporting members and a pair of inner yarn stick supporting members mounted on said shaft, and means to cause the members of one pair to be moved relatively to the members of the other pair, said means comprising a shaft mounted on a member of the outer pair, a worm on said shaft, a worm gear meshing with said worm and mounted rigidly on a second shaft, cranks fixed on 110 said second shaft and pins on each of the inner pair of stick supporting members whereby the rotation of said second shaft will cause the simultaneous movement of the inner supporting members.

115 9. In a yarn dyeing machine, in combination, a liquor vat, a shaft revolvable adjacent thereto, a series of inner yarn stick supporting members and a series of outer yarn stick supporting members mounted on said 120 125 stick supporting members mounted on said 130

shaft, and means to move the members of one series simultaneously relatively to the members of the other series, said means comprising a shaft mounted on the members of one series, cranks rigid on said shaft, pins on the members of the other series adapted to be engaged by said crank, and means to cause a rotary movement of said shaft.

In testimony whereof, we affix our signatures in the presence of two witnesses.
